G. R. HEBDEN

KNIFE SWITCH

Filed Feb. 2, 1925

FIG. 1.

FIG. 3.

FIG. 2.

FIG. 5.

FIG. 4.

INVENTOR
George R. Hebdon,

ATTORNEY

UNITED STATES PATENT OFFICE.

GEORGE R. HEBDEN, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

KNIFE SWITCH.

Application filed February 2, 1925. Serial No. 6,235.

To all whom it may concern:

Be it known that I, GEORGE R. HEBDEN, a citizen of the United States of America, residing at Plainville, county of Hartford, 5 State of Connecticut, have invented a new and useful Knife Switch, of which the following is a specification.

My invention relates particularly to switches having one or more swinging 10 blades.

The main object is to provide a post or jaw which can be made cheaply and to which the circuit wire or conductor may be directly connected.

15 A further specific object is to form a switch front or jaw from a single piece of metal. I have also sought to provide a simple and effective anchorage.

Fig. 1 is a perspective view of a switch 20 embodying the improvements of my invention.

Fig. 2 is an enlarged sectional view showing one of the switch jaws or posts attached to a support.

25 Fig. 3 is a side view of one of the posts with a conductor wire attached.

Fig. 4 is a perspective view of the blank from which a switch post or jaw may be formed.

30 Fig. 5 is a perspective view of the post partially formed and with a binding screw.

The post or jaw is preferably formed of a single strip of metal having a base 6, arms 7 and 8, with upright portions 9 and 35 10, and terminating in jaws or tip portions 11 and 12. One of the intermediate portions is preferably provided with a tubular member 13 adapted to register with the opening 14. This tubular member 13 is inferiorly threaded to accommodate the shank of a binding screw 15. This extension 13 may be riveted to more securely hold the two side arms together.

40 It should be noted that the shoulders 16 and 17 formed immediately above and below the head of the screw, serve to guide the conductor wire when connecting it and retain it in position beneath the head of the screw. I may also provide additional lugs, such as 18, 19, 20, and 21 around the head of the screw for the same purpose.

45 It will thus be seen that I provide in the single structure the combination of a sup-

porting post or jaw for a knife blade switch together with shoulders positioning the conductor where it may be held in place by a screw passing directly into the post without the necessity of any additional means, such as are commonly employed in switch constructions.

To facilitate the mounting of the switch parts I prefer to strike up from the base of the jaw, an extension 22, which is interiorly threaded to receive the attaching screw 23, which passes through the insulating base 24. To facilitate locating and retaining the post or jaw in position on the base 24 I may form recesses, such as 25, to receive the base portions of the posts. The insulating base 24 may be formed of fibre or other compressible material and the recess 25 may be formed by indenting or pressing-in the material of the base at the desired point or points.

The invention is of course also applicable 75 to the supporting post 26 to which the switch blade 27 is hinged, as well as to the spring jaw member 28 adapted to receive the switch blade, and in this case I, therefore, use the terms "post" and "jaw" interchangeably to apply to a construction of this character.

In the construction of contact jaw 28, it is preferable to rivet the end of the tubular projection 13 in place so as to secure the arms of the jaw together positively but in the construction of the hinge jaw 26, the blade 27 is secured in position usually by means of a rivet 29 which also secures the arms of the jaw in position, thus in this 80 later form it is not necessary to rivet the tubular projection 13.

I claim:

1. A one-piece knife blade switch jaw comprising a base, arms extending therefrom, one of said arms having a perforation and the other arm having an integral tubular projection extending into and riveted in said perforation, and a binding screw threaded into said projection.

2. A switch blade jaw member comprising a base, arms extending therefrom and spaced apart at their outer ends to receive a switch blade, integral means for securing the intermediate portions of said arms together, and a binding screw passing through said arms

at the point where they are secured together, one of said arms having projecting wire-retaining shoulders immediately adjacent the head of said screw.

5. 3. A one-piece knife switch jaw comprising a base, arms extending from the outer edges thereof and inclined toward each other, one of said arms having an opening and the other arm having an integral tubular projection secured in said opening, and a binding screw passing through said projection, the outer ends of said arms being spread apart beyond said screw to receive a switch blade and providing a shoulder immediately adjacent the head of said screw

for operating in conjunction with the head of said screw to retain a circuit wire.

4. A knife switch jaw comprising a base, arms extending from the outer edges thereof and inclined toward each other, one of said arms having an opening and the other arm having an integral tubular projection secured in said opening, and a binding screw passing through said projection, the outer ends of said arms being spaced apart beyond said screw to receive a switch blade, one of said arms having wire-positioning lugs disposed around the edge of the head of said screw. 25

GEORGE R. HEBDEN.
